UNITED STATES PATENT OFFICE.

HUGH COACHMAN ALLSTON, OF ADAMS RUN, SOUTH CAROLINA.

BARREL-MAKING MACHINE.

Application filed October 7, 1922. Serial No. 593,112.

To all whom it may concern:

Be it known that I, HUGH C. ALLSTON, a citizen of the United States, residing at Adams Run, in the county of Charleston and State of South Carolina, have invented new and useful Improvements in Barrel-Making Machines, of which the following is a specification.

This invention relates to barrel making machines.

The object is to improve the construction of barrel making machines, whereby barrels may be manufactured more expeditiously with a fewer number of operations and less handling on the part of the operatives, and consequently at much less cost than in the ordinary method of producing the same.

More specifically, the present machine is designed to be operated by two men and to hold and to form a barrel in its earlier stages of manufacture, wherein the sides or barrel proper is composed of two equal sections of slotted veneer, and to facilitate the introduction and application of the necessary inside and outside hoops at either end of the barrel, and to automatically staple the same in position.

Another object is to provide for the application of a wire hoop to the outside of the barrel prior to the fastening of the outside wooden hoops in order to conform to a Federal law requiring such metal hoops on all barrels intended for use in the transportation of potatoes and other vegetables, such hoops having heretofore been applied by hand as a separate operation.

A final object is to provide a barrel making machine which is simple of construction, may be manufactured at a moderate cost and may be easily and quickly operated by persons not necessarily skilled in the art to produce veneer barrels, which have the required strength and rigidity with the necessary inner and outer reinforcing and holding hoops secured thereto, at its ends, together with the said metal hoop, and to place them in condition for transfer to some form of shaping machine, such as shown and described in Patent Number 998,478, issued to J. F. East, July 18, 1911, on which machine, or any other similar machine, the barrel which, up to this stage, is in a tubular form, is given the usual bulge at the central portion thereof and the intermediate inner

and outer hoops are applied and secured in 55 position.

A full and complete understanding of the invention may be obtained from a consideration of the following detailed description, taken in connection with the accompanying drawings forming a part of this specification, it being understood that while the drawings show a practical form of the invention, the latter is not to be confined to strict conformity with the showing thereof, 65 but may be changed or modified, so long as such changes or modifications mark no material departure from the salient features of the invention, as specifically pointed out in the appended claims. 70

In the drawings, in which similar reference characters designate corresponding parts throughout the several figures:

Figure 1 is a front elevation of a barrel making machine constructed in accordance 75 with this invention;

Figure 2 is an enlarged detail, vertical sectional view, taken longitudinally through the formed barrel and showing the construction of the barrel holding heads; 80

Figure 3 is a vertical, transverse sectional view taken on the line 3—3 of Figure 2;

Figure 4 is a detail section through the clamp for holding the inner hoop in position on the expander head; 85

Figure 5 is a detail section through a portion of the expander head;

Figure 6 is a detail horizontal sectional view through the gearing at the upper left hand corner of the machine, as viewed in 90 Figure 1;

Figure 7 is an end elevation of the same;

Figure 8 is a plan view of one of the veneer blanks used in the construction of the body of the barrel; and 95

Figure 9 is a side view of the barrel as it is shaped by the forming machine.

Figure 10 is a detail view through the actuating shaft showing one of the clutch members. 100

Figure 11 is a plan view of the same.

In the ordinary method of forming veneer barrels the work is done by hand up to a certain stage before the barrel is operated on by the shaping or forming machine, such as the hereinbefore mentioned East machine. 105

The present invention is designed to do

the work formerly done by hand, to simplify the operation, and to eliminate the services of several operatives. This work consists in placing the two halves composing the barrel together, inserting inside wooden hoops at each end, together with outside hoops at each end, and a wire hoop in surrounding relation to the barrel, and abutting at the bottom end thereof against the outside hoop at that end. The wire hoop, which, as has been stated, is required by law on barrels for certain uses, could easily be put on by hand, but efforts heretofore to place the same in position while the elements of the barrel were being assembled and secured in position in a machine, have been unsuccessful. The present invention takes care of all this by providing means for easily slipping the necessary wire hoop over the barrel while the same is in position in the machine, so that the barrel is fully prepared and ready to be acted on by the East machine, or any other similar machine, for the purpose of bulging the body of the barrel and applying and securing in position the two spaced intermediate hoops on the inside and the outside of the barrel, as a final operation.

The wooden veneer, of which the barrel is formed, is cut into rectangular pieces substantially 27 by 29 inches, the latter dimension representing the approximate height of the finished barrel. As shown in Figure 8 of the drawing, the rectangular blank A is formed of wooden veneer being substantially one-quarter inch thick, and having equally spaced slits B arranged longitudinally thereof, that is, parallel to the 29-inch dimension or vertically of the finished barrel. These slits are formed entirely through the sheet of veneer and are equally spaced apart, being preferably nine in number so that there are ten staves therebetween, in each blank or half and twenty staves in the complete barrel, the ends of the slits B stopping short at each end, from the edge of the veneer blank A. Each blank A comprises one-half of the body of the barrel, and when curved into a semi-circular form, being 27 inches in length, will provide a diameter of substantially 17 inches on the inside of the barrel when the two halves are applied together in a manner to be described. The slits B, it will be understood, permit the staves therebetween to bulge outwardly after the finished barrel is operated on by the forming machine to give the same the usual shape, while the integral end portions of each blank serve to hold the barrel together at the top and bottom in conjunction with the several hoops placed thereon.

As shown in Figure 1 of the drawings, the improved machine consists of a supporting base 1, formed of some suitable

cast metal and having, adjacent to each end, perpendicular posts or standards 2, preferably formed integral therewith, and having their upper ends provided with outstanding flanges in the same horizontal plane and adapted to receive and support vertically disposed, tapered pedestals 3, which are suitably secured thereto, as by bolts or other fasteners. The upper ends of the tapered pedestals 3 are provided with alined horizontal bearings 4 for the reception of a longitudinal actuating shaft 5 adapted to operate the several elements of the machine in the proper timed relation.

Secured to the outer faces of the tapered pedestals 3 are angular brackets 6 having attaching plates 7 for the purpose of connecting the same to the pedestals by means of bolts or other fastening devices. This sectional construction greatly facilitates the assembling of the several parts of the machine, as well as any necessary repair work in the event of breakage. The upper ends of the angular brackets 6 are also provided with horizontal bearings 8 in alinement with the bearings 4, and adapted to receive the terminal portions of the actuating shaft 5.

The pedestals 3 are further provided with integral outstanding lugs or enlargements 9, suitably provided with sockets for the reception of the inner ends of short drive shafts 10, whose outer ends are mounted in eyes or bearings 11 formed in the upstanding portions of the angular brackets 6, the said shafts 10 being preferably held against rotation by set screws 12.

The posts 2 which are preferably formed of hollow construction, are provided adjacent to their upper ends, where connected to the pedestals 3, with horizontally disposed, alined, tubular bearings 13, passing entirely through the same for the purpose of mounting slidable and rotatable barrel-supporting heads therein.

The ends of the actuating shaft 5, where projecting slightly beyond the bracket bearings 8, extend into sleeves which are connected with crank discs 14 having the usual wrist pins 15, to which are suitably connected adjustable pitmen 16, the lower ends of which are connected to hinged extensions or links 17 adapted to swing independently of, and at right angles to the path of movement of the said pitmen 16, the lower ends of said extensions being, in turn, pivotally connected to the horizontally disposed arms of bell crank levers 18 pivoted at their angles, as at 19, to outwardly extended portions of the flanges at the tops of the posts or standards 2. The downwardly extending arms of the bell crank levers 18 are in turn connected to links 20, which have their inner ends pivoted to the terminals of relatively short shafts 21, which latter are adapted to support and to actuate the bar-

rel-supporting heads, in a manner to be described.

As thus far described, the two ends of the machine are identical in construction and, 5 together with certain other parts to be described, provide for the complete preparation of the barrel for the final operation of the forming or shaping machine.

Mounted within the tubular bearing 13 10 of the right hand post or standard 2 (as views in Figures 1 and 2 of the drawings), there is a bushing 22 suitably held from longitudinal movement therein, and in which there is adapted to revolve and to 15 slide a hollow shaft 23 having a bore fitting the aforesaid short shaft 21 on that side of the machine. The short shaft 21 and the hollow shaft 23 are considerably longer than the said bushing 22, and are 20 adapted to normally extend inwardly beyond the inner wall of the post or standard 2, the inner end of the hollow shaft carrying a circular barrel supporting head 24, which is preferably formed integrally 25 therewith. The adjacent inner end of the short shaft 21 is provided with a flange or head 25 bearing against the inner end of the hub of the head 24, and the outer end of said shaft is pivotally connected to the 30 aforesaid link 20 so that when the bell crank lever 18 on this side of the machine is actuated through the medium of the pitman 16 and the crank disc 14, the head 24 is moved longitudinally toward or away 35 from the adjacent post 2, the shafts 21 and 23 sliding together through the bushing 22 in the bearing 13. This manner of mounting the head 24 permits of the said movement thereof toward and away from the 40 center of the machine, and at the same time permits of a rotary movement of the said head in a step-by-step manner, which movements, as will be explained, are necessary in the formation of the barrel.

45 The head 24 is provided with an inwardly directed, peripheral flange 26, whose face is conical shaped or tapered, and ends in an outstanding flange constituting an abutment stop 27 against which the hereinbefore 50 described veneer blanks A are adapted to be placed together with the inner and outer wooden hoops C and D respectively, in a manner to be explained. The slideable head 24 is provided with a spring clip 28, secured to the outer face thereof and adapted to overhang the tapered flange 26 and to bear downwardly against the veneer to hold the same at this end of the machine.

60 The hollow shaft 23 carries, at its outer end, a ratchet wheel 29 having its inner face provided with a tapered hub 30, which is adapted, when the head 24 is forced inwardly by means of the bell crank lever 18, to frictionally engage between the correspondingly tapered ends of a pair of spaced,

outwardly extending lugs or enlargements 31, and to act as an automatic brake to immediately arrest the rotary movement of said head and, in addition, to stop the longitudinal sliding movement of the same inwardly so as to position the said head for the reception of the veneer blanks A and the hoops. 70

75 A vertically movable rod 32 having its lower end 33 bent outwardly at right angles, is adapted to engage and to actuate the ratchet wheel 29, the portion 33 acting as a dog to engage the teeth of the wheel and, by reason of its extension, to permit the wheel to be advanced outwardly or inwardly together with the head 24, while still maintaining such engagement. The upper end of the rod 32, which is supported pendently, is slightly deflected and provided, at its upper terminal, with a strap 80 for surrounding an eccentric 34, suitably secured to the actuating shaft 5 adjacent to the bearing 4, and adapted to be rotated to give the necessary movement to the ratchet wheel 29 and the head 24. 90

95 A drive pulley 35 having connected thereto a relatively small pinion 36 is loosely mounted on the short shaft 10 at this side of the machine, and said pinion is adapted to mesh with a larger gear wheel 37 loosely mounted on the actuating shaft 5 adjacent to the outer face of the eccentric 34. The outer face of the hub formed on the gear wheel 37 is provided as shown in Figures 10 and 11 with ratchet teeth, any one of which 100 may be engaged by a pin 37^a which is adapted to be projected by the spring 37^b, but is normally held retracted by clutch member 38 suitably pivoted on an arm 39 carried by the cap plate of the bearing 8, said mechanism being substantially the same as that shown and described in the said East machine. The clutch member 38, when actuated, permits the pin 37^a to connect the 105 loosely mounted gear wheel 37 to a coacting disc 40 journaled on the shaft and, through the medium of a suitable sleeve 40^c, to cause a rotary movement to the adjacent crank disc 14 at the proper time to withdraw the head 24 from the barrel. A portion of the 110 disc 40 is surrounded by a brake band 40^a carried by the arm 39 and adjustable, by means of a thumb-nut 40^b, to increase tension on the band to frictionally stop rotary movement of the crank disc 14 when the 115 clutch is disengaged. The said crank disc is actuated one-half a revolution at each actuation, through proper timed movement of the foot pedal 42 to thus slide the barrel-supporting head 24 to its innermost and 120 outermost positions.

125 The clutch member 38 is actuated by a push rod 41 extending downwardly to the base plate 1, and is there connected to a foot pedal 42 extending inwardly to within easy 130

reach of the operator at this side of the machine, it being understood that two men are employed to control the machine, one in front and one in rear of the same. A retractile spring 43 is connected to the inner free end of the pedal 42, and to the adjacent face of the post or standard 2, to elevate the pedal when pressure of the foot is released, and to disconnect the gear wheel 37 from the actuating shaft, so that rotary motion from the drive pulley 35 will not be imparted to the shaft or crank disc.

Any suitable form of barrel hoop feeding and stapling mechanism may be employed at each end of the machine, similar means to that employed in the East machine being indicated at 44 in the drawing, the same being supported in position on a detachable arm 45 bolted to the front face 20 of the pedestal 3, and having means for proper actuation by eccentrics 46 mounted on the actuating shaft 5 and adapted to feed the strips forming the hoops and to staple the same when actuated.

25 The short shaft 21 at the left hand end of the machine is pivotally connected at its outer end to the adjacent link 20, and is adapted to be moved longitudinally thereby through the medium of the bell crank lever 18 and the crank disc 14, such movement being, however, provided not for the purpose of moving the head 47 in a like manner, but to cause the actuation of expanding mechanism to be described.

35 The head 47, as clearly shown in Figure 2 of the drawing, is preferably formed integrally with an extended hub or sleeve 48, fitting in the adjacent bearing 18 and extending through the same, where a retaining collar 49 is secured thereto to prevent the same from longitudinal movement, the said hub having an integral disc 50 formed thereon and abutting against the inner face of the adjacent post or standard 2 to prevent outward movement of the head, said disc acting as a brake in conjunction with a surrounding band 51 adjustably secured to the post 2 and adapted to arrest the rotary movement of the head 47, such movement being imparted thereto in a step by step manner, by means about to be described.

55 Adjacent to the disc 50, and between the same and the head 47, the hub or sleeve 48 carries a ratchet wheel 52 adapted to be engaged by a pendant rod or dog 53 having connection with and adapted to be actuated by an eccentric 54 similar to the aforesaid eccentric 34 on the other end of the machine. The rods 32 and 53 give the desired step by step movement to the heads 24 and 47 respectively by reason of the engagement of the same with the teeth of the ratchet wheels 29 and 52.

60 The expander head 47 is provided on its inner face, with a series of dove-tailed slots

or seats 55, preferably four in number, (Fig. 3), the same being arranged radially to the center of the head and extending inwardly from the periphery thereof substantially half way to the center. Seated within these slots are sliding blocks 56 somewhat shorter than the lengths of the slots and dove-tailed to fit the same. The inner end of the adjacent short shaft 21 extends inwardly beyond the inner face of the head, and is there provided with spaced sets of outstanding arms between which are pivoted spreader links 57, whose outer ends are, in turn, pivoted in slots 58 provided in the inner ends of the sliding blocks, so that, when the short shaft 21 is reciprocated outwardly through the medium of the bell crank lever 18 and the adjacent crank disc 14, the movement causes the links 57 to force the sliding blocks 56 outwardly within the dove-tailed seats 55.

The outer ends of the blocks 56 carry arcuate hoop seats, in the form of segments 59 (Fig. 4), the same having, on their outer marginal edges, upstanding flanges 60, and the length of the segments is such that when the blocks are in their innermost position in the slots 55, the outer portions of the same rest upon the periphery of the head 47 and they form, in effect, a continuous circle of a diameter substantially equal to the internal diameter of the finished barrel, which is generally about seventeen inches.

30 Each flange 59 overhangs the inner face of the head 47 and is provided at its center in line with the spreader links 57, with a marginal lug 61 whose outer face is inclined, as clearly shown in Figure 4 of the drawings, and facilitates the placing of the inner hoop E thereon, said hoop being cut at a length to provide the proper diameter to fit the inside of the finished barrel, at the bottom end thereof, which end is designed to be handled by this side of the machine, the upper end of the barrel being handled by the first described or right hand end of the machine.

35 The periphery of the head 47 is provided with a slot 62, in which is pivotally mounted a clamp 63 bent substantially at right angles to overlie the central part of one of the segments 59, and having its end tapered to facilitate its rocking movement by the finger of the operator in order to provide room for placing the said inner hoop E thereunder and behind the inclined lugs 61. The pivot of the clamp is surrounded by a coiled spring 64 having its ends suitably anchored to cause the clamp to normally press downwardly against the outer face of the inner hoop E and to hold the free ends thereof, while the elements are being placed in position prior to stapling by the devices 44, the flange 60 being provided with an open-ended slot 65 to allow

the longitudinally disposed portion of the clamp 63 to move therein for such purpose.

In order to secure the proper timed relation of the expanders, it is necessary to reduce the speed of the left hand end of the machine and in order to do this it is necessary to interpose reducing gears between the drive pulley and the actuating parts.

- 10 The drive pulley 66 together with the connected pinion 67 are formed similarly to the pulley and pinion first described, and are mounted on the adjacent shaft 10 in the same manner to revolve independently thereof. The pinion 67 is in mesh with a gear wheel 68 loosely mounted on the actuating shaft 5 between the bearings 4 and 8 and is constantly driven thereby, said gear wheel being adapted to be connected 20 to or disconnected from a member 69^a, secured to the said shaft 5, by means of a clutch mechanism 69 which is similar to the clutch mechanism 38 at the other end of the machine and which is illustrated in detail 25 in Figures 10 and 11, and adapted to be controlled by a push rod 70 having connection at its lower end to a foot pedal 71 arranged on the same side of the machine as the pedal 42 and adapted to be operated by the same operator, a coiled spring 72 being connected to said pedal and to the adjacent post or standard 2, for the purpose of normally elevating the pedal and disconnecting the gear wheel 68 from the shaft 5.

35 The opposite face of the gear wheel 68 is provided with clutch elements for coaction with the clutch 73 carried by an arm 74, similar to the aforesaid arm 39 and mounted on the cap plate of the adjacent bearing 8, said clutch 73 being formed similarly to the clutches 38 and 69 and adapted to be actuated by the push rod 75 connected to a foot actuated pedal 76 located at the rear side of the machine, the inner end of which extends to the center of the machine and is retracted by a spring 77.

40 The clutch mechanism 73 is adapted to connect a loosely mounted pinion 78 to the gear wheel 68 so as to cause rotation of the pinion, and when the gear 68 is connected by the clutch 69 to the member 69^a which is secured to the shaft 5, said shaft is caused to rotate.

45 The adjacent crank disc 14 is carried by a sleeve 79 mounted in the bearing 8 and in surrounding relation to the end of the actuating shaft 5, the said sleeve 79 having secured on its inner end a gear wheel 80 abutting against the pinion 78 on one side but independent thereof and against the bearing 8 on the other side.

50 The adjacent bracket 6 is provided with a forwardly extending angular arm 81 formed integrally therewith and having, at its forward upper end, a clamping bearing

82 in which is secured a short stub shaft 83, on the inner end of which is mounted a double gear having a larger gear 84 in meshing relation to the aforesaid pinion 78 loose on the shaft 5, and also having a small gear 85 which is in mesh with the gear wheel 80 connected to the adjacent crank disc 14. By this arrangement the speed of the crank disc is properly reduced below the speed of the gear wheel 68, which is constantly driven by the belt pulley 66 and the interposed pinion 67. Automatic brake mechanism 86, similar to 40 and 51, is carried by shaft 5, to check the latter.

55 In the operation of the machine, a pile 80 of the veneer blanks formed and slotted as hereinbefore described, are placed on the base plate 1 between the standards 2. This locates the same between the foot pedals and within easy reach of the operators, the same being immediately beneath the two barrel holding heads 24 and 47. A number of iron wire hoops F previously formed in a diameter to snugly fit the outside of the finished barrel, are placed over the expanding head 47 and rest upon the exposed portion of the sleeve or hub 48 between the head and the adjacent ratchet wheel 52, so that the said rings or hoops F are within easy reach of the operators.

60 First the inside wooden hoop E for the bottom end of the barrel is placed on the expanders 59 and behind the lugs 61, the said expanders being at their innermost position or retracted and the ends of the strip comprising the inner hoop being held by the clamp 63. The inner hoop, as well as all other wooden hoops used in the construction of the barrel, is composed of elm wood, which is strong and pliable and is fed into position by the mechanism indicated at 44 at each end of the machine, which mechanism also includes means for stapling the hoops in position and for feeding and tensioning the wire for the staples. This inner 65 hoop E is one inch in width and snugly fits between the flange 60 and the straight inner wall of the inclined lugs 61 and is adapted to snugly surround the several arcuate segments 59, the ends being somewhat overlapped and held by the clamp 63 to allow for expansion later and to be properly stapled.

70 At this time the inside wooden hoop C for the open end of the barrel is fed into position in surrounding relation to the sliding head 24, said hoop resting on the inclined or tapered flange 26 thereof, the overlapped ends of the hoop being engaged beneath the spring clip 28 which holds the same temporarily.

75 The two halves of the body of the barrel consisting of two of the veneer blanks A are then placed by hand on the heads 24 and 47 and around the outside of the inner hoops C and E, the slits B of said blanks

A running longitudinally of the machine and the imperforate end portions thereof resting on the said heads. The veneer at the left hand end bears upon the outside of 5 the clamp 63, with one of the seams between the blanks at the top and the other at the bottom of the heads, the edges being flush at the top and held by the springs 28. The spring 28 thus holds the veneer blanks at 10 the top on the right hand end, while the left hand end of the blanks at their upper meeting edges are held by hand, the lower, free edges of the two blanks being held by the knees of the two operators, 15 one on each side, while one of said operators removes one of the wire hoops F and slides the same over the head 47 beneath the stapling device and, while the veneer is contracted, pushes the said ring onto 20 the body of the barrel to a position near the center of the same, which serves to temporarily hold the veneer in tubular form, the lower free edges being thus caused to remain in juxtaposition, or near thereto. 25 Now the pedal 76 is depressed to lock gear 68 to pinion 78 when the latter serves to drive the gear 84 and pinion 85, together with gear 80, at reduced speed, and which being mounted on the sleeve 79 with the adjacent crank disc 14, will actuate the expanders 59 to the predetermined diameter for the proper internal dimensions of the barrel. Up to this time the lower seam is somewhat overlapped at the expander end 30 only, and when the pedal 76 is thus depressed to actuate the expanders, this overlapping disappears, and the overlapping of the ends of the inner hoop is just the proper amount for stapling. 35 Now the pedal 71 is depressed thus locking the member 69 to the gear 68 and causing the shaft 5 to rotate, the other train of gearing 78, 80, 84 and 85 having been thrown out of gear by the retractile spring 40 77 on pedal 76, and the eccentrics 34 and 54 are rotated to cause a step by step rotary movement of the barrel, at the same time the outside elm hoop G which is preferably one and one-half inches wide, is automatically fed on around the bottom end of the barrel while the outside hoop D, at the upper end of the barrel, which is preferably one inch in width, is simultaneously fed on 45 automatically around the revolving barrel, and the two hoops, together with the ends of 50 the veneer blanks and the inner hoops are stapled in place by the automatic stapling mechanism 44, the said outside hoops overlapping at the ends, as usual. The hoop D 55 is spaced away from the end of the veneer to allow room for the final hoop for holding the usual jute covering, or other cover, to be placed in position, and it should be stated that the inner hoop C which is with- 60 65 in the open or upper end of the barrel, is

preferably three inches in width to reenforce the ends of the veneer from within and allow the fastening of the said final hoop in place.

Now the pedal 76 is again depressed to 70 connect gears 84 and 85 with 78 and 80, when the crank disc 14 at the left hand end of the machine will be revolved one-half revolution to release the expanders. The 75 pedal 42 is then depressed to actuate the crank disc 14 at the right hand end of the machine one-half revolution, and withdraw the head 24 to release the barrel which is forced from engagement with the clamp 63, 80 which is now located at the top of the head 47, and the barrel drops from the machine, the wire hoop F being then forced downwardly against the upper edge of the outside, bottom, wooden hoop G, and the barrel is then taken to the East machine or other 85 shaping or forming machine similar thereto, to be shaped. This machine, by means of certain intermediate expanders gives the usual bulge to the sides thereof, the slits B opening to form staves, and inner and outer intermediate hoops are fastened in place to maintain such shape, as indicated in dotted lines at H in Figure 9 of the drawing. 90

What is claimed is:—

1. A barrel making machine comprising 95 opposed standards, barrel supporting elements carried by the standards, one of said elements including expanding means for one end of the barrel, the other element being bodily slidably longitudinally of the barrel to free the same from the other end of the barrel when the operation is completed, a shaft mounted on said standards above the barrel supporting elements, and means supported on said shaft to operate the barrel 100 supporting elements selectively. 105

2. A barrel making machine comprising 110 opposed standards, barrel supporting elements carried by the standards, one of said elements including expanding means for one end of the barrel, and having means for engaging and holding the inner hoop at that end, the other element being bodily slidably longitudinally of the barrel to free the same from the other end of the barrel when the operation is completed, a shaft mounted on 115 said standards above the barrel supporting elements, and means supported on said shaft to operate the barrel supporting elements selectively. 120

3. A barrel making machine comprising 125 opposed standards, barrel supporting elements carried by the standards, one of said elements including expanding means for one end of the barrel and having a spring-pressed pivoted clamp for engaging the inner hoop for holding it on the expanding means, the other element being bodily slidably longitudinally of the barrel to free the same from the other end of the barrel when 130

the operation is completed, a shaft mounted on said standards above the barrel supporting elements, and means supported on said shaft to operate the barrel supporting elements selectively.

4. A barrel making machine comprising a pair of opposed standards, independently movable means mounted on the respective standards for supporting and operating on 10 the barrel, said means including opposed spaced heads adapted to fit into the open ends of the barrel being formed, one of said heads having means for expanding one end of the barrel, and the other end having 15 means for withdrawing the same from the barrel to release the barrel, a shaft mounted on said standards, a pair of gear wheels journaled on the shaft, means for rotating said gear wheels, means for operatively connecting one of the gear wheels to the expanding means, and means for operatively connecting the other gear wheel to the withdrawing means.

5. A barrel making machine comprising a 25 pair of opposed standards, barrel supporting elements carried by the respective standards, one of said elements including a head having arcuate segments fitting within the barrel, each segment being provided 30 with a lug on the edge facing the center of the barrel and also having a continuous flange on the other edge, a clamping device carried by said head to engage over a hoop held between the lug and flange, and means 35 carried by the other head for holding the veneer against the outside of said hoop.

6. A barrel making machine comprising a pair of opposed standards, barrel supporting elements carried by the respective standards, 40 one of said elements including a head having a spring-pressed pivoted clamp for engaging the inner end hoop to hold it against the head, means associated with the last mentioned element for expanding the hoop while 45 the veneer is held against the same, the other element being bodily slideable longitudinally of the barrel to free the same from the end of the barrel when the operation is completed, said second mentioned head having 50 means for engaging and holding the veneer until it is secured in place.

7. A barrel making machine comprising a pair of opposed standards, barrel supporting elements carried by the standards, one of 55 said elements including a head having means for engaging and holding the inner hoop at that end, means associated with the last mentioned element for expanding the hoop while the veneer is held against the same, the other element having means for holding the veneer while the operation is being performed and being bodily slideable longitudinally of the barrel to free the same from the barrel when the operation is completed, the head having the expanding means being

provided at its outer side with means for supporting a plurality of metal hoops.

8. A barrel making machine comprising a pair of opposed standards, barrel supporting elements carried by the respective 70 standards, one of said elements including a head provided with means for clamping an inside end hoop, means for extending said head to expand the hoop held thereby, the outer element being tapered and adapted to support an inside hoop for the other end with the veneer upon the hoop and also having means for engaging the abutting ends of the veneer for retaining the same in place upon said inside hoops, and means for withdrawing the last mentioned element from the barrel after the operation is completed.

9. A barrel making machine comprising a base having spaced standards thereon, a continuous actuating shaft mounted at the 85 upper ends of the standards, separate driving means on the standards for selectively expanding one head and imparting a bodily movement to the other, clutches for disconnecting the driving means from the heads 90 and revolving the shaft to cause a step by step rotation of said heads, hoop feeding and stapling mechanisms mounted over the heads, and means carried by the revolving shaft to actuate the said mechanisms 95 between the steps.

10. A barrel making machine comprising a base having spaced standards, one standard carrying a circular head adapted to receive one end of the barrel and the other standards 100 having a circular head adapted to receive the other end of the body of a barrel, said last named head having means for expanding that end of the barrel, an actuating shaft mounted at the top of the standards, stub shafts mounted on each standard and having each a driving pulley and pinion mounted thereon, loosely mounted gear wheels on the shaft and meshing with the pinions, clutches for locking the gear wheels to the shaft to 105 impart rotary motion thereto, means for operating the expanding means to increase the diameter of that end of the barrel, and speed-reducing gearing interposed between the shaft and the expanding means to 110 properly time the latter.

11. A barrel making machine comprising a base having spaced standards, one standard carrying a circular head adapted to receive one end of the barrel, said head 120 being movable longitudinally out of the end of the barrel, and the other standard having a circular head adapted to receive the other end of the body of a barrel, said head having means for expanding that end of the barrel, an actuating shaft mounted at the top of the standards, stub shafts mounted on each standard and having each a driving pulley and pinion mounted thereon, loosely mounted gear wheels on the shaft 125 130

and meshing with the pinions, clutches for locking the gear wheels to the shaft to impart rotary motion thereto, a crank disc carried by the end of the shaft, a bell crank lever mounted on the adjacent standard, a pitman connecting the disc to the bell crank lever, a shaft carrying the movable head and slidably mounted in the standard and having its free end connected to the bell crank lever to cause the head to leave the barrel when the disc is rotated one-half revolution.

12. A barrel making machine comprising spaced standards, barrel-supporting elements carried by the standards, one of said elements including a head for one end of the barrel with expanding means therefor, and the other element including a head for the other end of the barrel with means for withdrawing said head from the barrel, a common actuating shaft mounted at the top of the standards, gearing for driving both heads from said shaft by a step-by-step rotary movement, separate means connected with the opposite ends of the shaft for actuating the expanding means of one head and for actuating the withdrawing means of the other head, said separate means being actuated independently of the driving means.

13. A barrel making machine comprising a pair of opposed standards, barrel supporting elements carried by the respective standards, one of said elements including expanding means for one end of the barrel, the other element being bodily slidably longitudinally of the barrel to free the same from the adjacent end of the barrel when the operation is completed, a shaft mounted on said standards above said barrel supporting elements, means supported on said shaft to operate the barrel supporting elements

selectively, means for rotating said shaft, and means operable by the rotation thereof to impart a step by step rotation to the barrel supporting elements.

14. A barrel making machine comprising a pair of opposed standards, independently movable means mounted on the standards for supporting and operating on the barrel, said means including a pair of opposed spaced heads adapted to fit into the open ends of the barrel being formed thereon, one of said heads being expansible and the other being movable longitudinally to withdraw the same from the barrel, a shaft mounted on said standards, a pair of gear wheels journaled on the shaft, means for rotating said gear wheels, means for operatively connecting one of the gear wheels to the expanding means, separate means for operatively connecting the other gear wheel to the longitudinally movable head, independent means for connecting one of said gear wheels to the shaft for rotating the latter, and means operable by the rotation of said shaft to rotate both barrel supporting means step by step.

15. A barrel making machine, comprising a pair of opposed standards, opposed barrel supporting elements carried thereby, means on each of said supporting elements for clamping an inside end hoop, means for holding the veneer in contact with the outside of the hoops, means associated with one of said supporting elements for expanding the hoop and veneer so held, and means for rotating both supporting elements step by step to apply the staples.

In testimony, that I claim the foregoing as my own, I have hereto affixed my signature.

HUGH COACHMAN ALLSTON.
